UNITED STATES PATENT OFFICE.

WILLIAM M. GARVIN, OF BLACKVILLE, SOUTH CAROLINA.

METALLIC ROOFING.

No. 892,248.

Specification of Letters Patent.

Patented June 30, 1908.

Application filed April 24, 1907. Serial No. 369,942.

To all whom it may concern:

Be it known that I, WILLIAM M. GARVIN, a citizen of the United States, residing at Blackville, in the county of Barnwell and State of South Carolina, have invented certain new and useful Improvements in Metallic Roofing, of which the following is a specification.

My invention relates to metallic roofing, and more particularly to that class of roofing which is formed into sheets of given size at a factory, and provided with edges so crimped or otherwise formed that the sheets may be applied to the roof by unskilled labor, and without the use of special tools. Heretofore it has been common to provide such sheets of roofing with U- or V-crimped edges, adapted to overlap, and to secure them to the sheeting by means of nails, driven through such crimped edges, or of cleats, overlying such edges. But it has been found that wherever the cleats are thus partly exposed to the weather, or where the roofing sheets are perforated by nails, rapid deterioration of the roof, due to oxidation of the fastenings, takes place.

It is therefore one object of the present invention to provide a roofing sheet having its edges so shaped that two adjacent edges will interlock so as to form a substantially watertight joint, without subsequent crimping.

A further object of the invention is to provide means for securing the roofing to the sheeting without puncturing the roofing sheet.

A further object is to provide a cleat for fastening the roofing sheets which shall lie wholly underneath the same and be protected from the weather.

With the above and other objects in view, the invention consists of the construction hereinafter described, and illustrated in the accompanying drawings, in which:

Figure 1 is a perspective view showing a fragment of my improved roofing sheet together with a cleat for holding the same in position. Fig. 2 is an end view showing the method of placing two sheets together so as to interlock. Fig. 3 is a sectional view on an enlarged scale, showing the two sheets in position so as to form the seam.

Referring to the drawings in detail, 1 represents my improved roofing sheet, which may be of any suitable width, and of a length which may be readily handled. This sheet 1 is formed at its edges with upstand-

ing flanges, for forming an interlocking seam. One flange consists of a slightly inclined substantially vertical portion 2, bent over at its top, as at 3, and merging into a depending vertical portion 4. This, in turn, is folded at its lower edge 5, and bent inwardly and upwardly to form a vertical upstanding portion 6. This flange conforms in shape to what I shall refer to as an inverted U-crimp with inturned edge. The other edge of the roofing sheet is provided with an upstanding flange formed into what I shall term a reverse or double-V-crimp. This flange consists of three substantially flat portions adjoining each other, the lower portion 7 rising at an acute angle from the sheet 1. The upper portion 9 is substantially parallel with 7, and the middle portion 8 lies between them, making an obtuse angle with both, and forming the ridges 11 and 12. The roofing sheet 1, and each of the portions 7, 8, and 9 of the flange, all lie in different planes. The roofing sheets are held in position by means of cleats, such as 20. These consist of angular sheet metal clips, having a base portion provided with holes 21, for the reception of nails 25, or the like, and an upstanding portion 22, folded over at its top 23, to form a depending flange 24.

Fig. 2 shows the method of assembling the sheets into position on the roof. The upper portion 9 of the flange of one sheet, is slipped sidewise under the U-crimp 5, of the sheet previously laid, and then by bearing down on the outer edge of the second sheet, as shown by the arrow, it pivots and slides about the corner 10, and such movement causes the portion 8 to enter under the edge 5 with a wedging action, and when the second sheet 95 has been rocked down so as to lie flat against the sheeting, the reverse V-crimp will occupy the position shown in Fig. 3. Before placing the second sheet in position however, the first sheet is secured in place by means of the cleats 20. These cleats are preferably formed and assembled in place when the sheet is formed. They lie within the inverted U-crimp, the part 23 nesting with 3 and are slidably held therein, so that they 105 may be slipped along lengthwise the sheet, and adjusted to any desired position before being nailed down. In some cases, as for instance, where the sheets are short, it may be desirable to have the cleats separate, and 110 slip them endwise under the flange, as needed. These cleats may be freely nailed.

to the sheeting before the next sheet is laid, and it is obvious that when the next sheet is brought to its final position, as shown in Fig. 3, it will overlie such nail heads, and the 5 cleats will be entirely protected from the weather. It will be noted that when first secured in position they engage the roofing sheets only on the inside of the upturned portion of the U-shaped flange. The next 10 sheet is then inserted, as shown in Fig. 2, and when in final position, as in Fig. 3 it will be seen that the cleat also embraces the V-crimp of the sheet which it underlies. The 15 slideable arrangement of cleats above described, permits of the ready expansion and contraction of the roofing sheets, due to changes in temperature, without in any way tending to loosen their fastenings.

From an inspection of Fig. 3 it will be seen 20 that the interlocking flanges engage or contact with each other at a plurality of points. The bend 5 engages tightly against the portion 8 of the double-V-crimp, while edge 6 engages the portion 9, and the edge 12 bites 25 against the cleats also.

The portion 7, extending as it does at an acute angle to the sheet 1, serves to deflect the water away from the joint 5-8. This 30 joint forms a substantially water-tight seal, but should any water leak past, it still would have to work past the joint formed by the edge 6, and the overhanging flange 9 would deflect it into trough 5, from the lower end of which it can escape.

35 It will be seen that I have provided a very simple and efficient system of roofing which may be placed in position very readily without special tools, and which forms a tight seam without subsequent crimping, and it is 40 thought the numerous advantages of the same will be readily appreciated by those skilled in the art.

What I claim is:—

1. A sheet of metal roofing provided at one 45 edge with an upstanding flange consisting of a plurality of V-crimps facing alternately to the right and left.

2. A sheet of metal roofing provided at one edge with an upstanding flange, said flange 50 being reversely crimped so as to form a plurality of ridges, facing alternately in opposite directions.

3. A sheet of metal roofing provided at one edge with a flange composed of an upstanding portion forming an acute angle with the sheet, an intermediate portion, reversely bent, and an upper portion substantially parallel to the first.

4. A sheet of metal roofing provided at one 60 edge with an upstanding flange comprising a plurality of reversely formed crimps, facing alternately to the right and left, and provided at the other edge with an inverted U-shaped flange.

65 5. In a metal roof, roofing sheets formed

with inverted U-shaped flanges having in-turned portions, and cleats, shaped to underlie one sheet, and engage the inturned flange of the next preceding sheet, all of the parts being assembled in final form without changing their original shape.

6. In a metal roof, roofing sheets provided at their edges with flanges of different types, one flange being U-shaped in cross-section and the other being crimped in a direction 75 parallel with the roof, so as to form a plurality of angular ridges, said flanges being so shaped that they may be rocked sidewise into engagement, and when so engaged, the U of the first flange will embrace the ridges 80 of the second.

7. In a metal roof, a roofing sheet formed with an inverted, U-shaped flange along one edge, and a second roofing sheet provided with an upstanding flange crimped in a direction parallel with the roof, so as to form a plurality of angular ridges adapted to interlock with said first flange with a wedging action, and engage the same on both sides 85 of the U.

8. In metallic roofing, roofing sheets provided with U-shaped and upstanding V-crimped edge flanges, the V-crimp of one sheet being formed parallel with the roof, and adapted to enter the U of the next with a 95 wedging action, and engage therewith at a plurality of points.

9. In a metal roof, roofing sheets provided at one edge with inverted U-shaped flanges, having in-turned portions, and at the other, 100 with flanges comprising a plurality of reversely formed V-crimps, said U- and V-flanges adapted to interlock at a plurality of points, and cleats formed to underlie the sheets and engage both the in-turned portion 105 of one flange and the upper edge of the other.

10. In a metal roof, a roofing sheet ready for laying provided at one edge with an inverted U-shaped flange, having an in-turned portion and a cleat shaped to engage and 110 underlie said flange without subsequent crimping, and slidably secured therein.

11. In a metal roof, roofing sheets formed ready for laying, and provided at one edge with an upstanding, angular flange, and at 115 the other with a curved, overhanging flange, cleats underlying said sheets and shaped to engage the inside of said overhanging flange, the construction being such that the flanges of two adjacent sheets may be locked sideways into engagement, and when in position, interlock to form a tight joint without subsequent crimping.

In testimony whereof, I affix my signature in the presence of two witnesses.

WILLIAM M. GARVIN.
